FLUE TOP

Phill Chancellor, Salem, Ohio

Application March 12, 1940, Serial No. 323,556

1 Claim. (Cl. 98—66)

This invention relates to a flue top and more particularly to a device for preventing down drafts in a vertically extending flue without interfering substantially with the normal flow of air or gases through the flue.

It is well known that in various flue installations, particularly that of a chimney whose function is to carry away smoke and gaseous products of combustion, that certain meteorological conditions which interfere with the proper functioning of the flue arise from time to time to seriously interfere with the operation of the furnace, burners or other apparatus which the flue serves. These conditions often cause a downward surge or flow of air in the flue and it is the primary object of the present invention to provide an apparatus which will prevent such downward surges or flow of air under all conditions of weather and environment.

A further object of the invention is the provision of an apparatus having the characteristics pointed out above but which may be economically constructed, readily applied to existing flues and which does not interfere with the normal functioning of the flue.

These and other objects and advantages of the invention should become apparent from a consideration of the following detailed specification and the accompanying drawing wherein there is specifically disclosed a preferred embodiment of the invention.

In the drawing:

Figure 1 is a side elevation of an apparatus constructed in accordance with the invention, the apparatus being shown as applied to a conventional flue, the latter being shown in section;

Figure 2 is a horizontal section of the apparatus taken along the line II—II of Figure 1; and

Figure 3 is a fragmentary sectional view taken along the line III—III of Figure 2.

The apparatus in its preferred and illustrated embodiment includes a sleeve 10 which is conveniently constructed of sheet metal and adapted to be received within the upper end of a vertically extending flue 16. It is desirable that the lower end of the sleeve 10 be tightly received within the flue and in practice the peripheral contour of the lower end of the sleeve is similar to the inner shape of the particular flue to which the apparatus is to be applied.

Sleeve 10 is tapered inwardly toward its upper end and progresses in peripheral contour from the inner shape of the flue at its bottom to a circle at its top. Secured to the upper end of

the sleeve 10 is a flat flange 11 which extends out over the top end surface of the flue 16, thus providing a support for the apparatus.

Extending upwardly from and securely fastened to the flange 11 are a plurality of inwardly curved walls 13, preferably four in number, which terminate short of each other to provide a plurality of vertically extending openings 20 equally spaced about the outer periphery of the apparatus. A horizontally disposed ceiling member 15 is positioned on top of the walls 13, being preferably also constructed of sheet metal, and fastened to the walls by any suitable expedient. A conical roof 14 overlies the ceiling 15 and completes the apparatus. It should be observed that the roof 14 extends outwardly beyond the walls 13 and the openings 20 and this, together with the conical shape of the roof, diverts any downward flow of air from the passages leading to the flue 16.

The operation of the apparatus described above should be readily apparent. In the event of a downward flow of air in the apparatus' environment, the roof 14 will function to divert the flow away from the vertical openings 20 leading to the space within the flue. If the flow of air is directed angularly downwardly the substantial part of the flow will again be diverted by the roof and only that portion which can enter one or two of the openings 20 will pass into the apparatus. This component, however, will be deflected upwardly by the flat surface of the flange 11 and will be drawn out of the apparatus through the other of the openings 20. The flat surface of the flange 11 cooperating with the flat and uninterrupted ceiling 15 provides an unrestricted passage for the horizontal movement of air through the apparatus and eliminates recesses and pockets which would cause the air to swirl and build up a positive pressure in the apparatus which would result in a down draft. By referring to Figure 2, which indicates by means of arrows the horizontal component of flow through the apparatus, it can be observed that quantity of air entering the apparatus is determined solely by the frontal areas of the openings 20 presented to the direction of air flow. This total area is small in proportion to the total obstructual area of the apparatus and is definitely less than the effective area of the other of the openings 20. By reason of the curvature of the side walls 13 the said effective area is at all times subjected to an exhausting force and, therefore, the average pressure within the ring 12 where the sleeve 10 meets the flange 11

will always be less than the average pressure of the atmosphere immediately surrounding the apparatus and this, of course, insures the proper functioning of the flue under all conditions.

Figure 2 illustrates a condition where the flow of air is directed toward one of the openings 20 and in this situation the volume of air passing into the apparatus is determined by the cross-sectional area of the one opening. Theoretically we can assume that this volume of air passes directly through the apparatus and exhausts therefrom at the opening diametrically opposite. The air impinging against the inwardly curved walls 13 immediately adjacent the first named opening will be caused, by reason of the curved surfaces, to be diverted outwardly along the outer reaches of the curved surfaces and as these volumes of air move past those openings 20 which are at right angles to the first named opening, the air and gases within the apparatus will be sucked out through those openings.

The above specifically described embodiment of the invention should be considered as illustrative only as obviously many changes may be made therein without departing from the spirit or scope of the invention as defined in the appended claim.

The term flue as used throughout the specification and claim is to be taken as meaning any channel or passage for smoke, air, gases of combustion or other gases as the invention is equally applicable to these various uses. For example, the apparatus of the invention may be

advantageously applied to the discharge end of a ventilating duct or shaft.

What I claim is:

Apparatus of the character described comprising in combination an upwardly tapering sleeve adapted to fit within the upper portion of a flue, a portion of said sleeve having a peripheral contour corresponding to the inner shape of the flue whereby the sleeve may be closely fitted within the flue, a flange secured to the upper end of said sleeve and adapted to overlie the top end of said flue, a plurality of side walls extending upwardly from the outer portion of said flange, said walls terminating short of each other to provide a plurality of circumferentially spaced but diametrically opposed vertically extending openings unobstructed in laterally or horizontally outward directions to allow unimpeded flow of air transversely through an opposed pair of said openings and across the open top of said sleeve, said walls being curved about vertical axes positioned outwardly of and intermediate said openings, the radius of curvature of said walls being greater than half the mean lateral dimension of the flue opening whereby a portion of an air flow impinging laterally on said walls will be deflected outwardly to create a suction about certain of said openings which are circumferentially spaced from said opposed pair of openings, and a roof over said walls extending outwardly of said walls.

PHILL CHANCELLOR.
